(57) **CLAIM**

The ornamental design for a fire hydrant shaped lawn sprinkler, as shown and described.

DESCRIPTION

FIG. 1 is a perspective view of the fire hydrant shaped lawn sprinkler showing our new design.

FIG. 2 is a first side view of the fire hydrant shaped lawn sprinkler showing our new design.

FIG. 3 is a second side view of the fire hydrant shaped lawn sprinkler showing our new design.

FIG. 4 is a back view of the fire hydrant shaped lawn sprinkler showing our new design.

FIG. 5 is a front view of the fire hydrant shaped lawn sprinkler showing our new design.

FIG. 6 is a top view of the fire hydrant shaped lawn sprinkler showing our new design; and,

FIG. 7 is a bottom view of the fire hydrant shaped lawn sprinkler showing our new design.

The broken line showing of portions of the sprinkler is included for the purpose of illustrating and forms no part of the claimed design.
